Primary Examiner—Daniel P Stephenson(74) *Attorney, Agent, or Firm*—Cantor Colburn LLP(57) **ABSTRACT**

Disclosed herein is a downhole plug protection system. The system includes, a tubular having perforations in a perforated portion, a screen in fluidic communication with the tubular, and a ring in sealable communication with the tubular and attached to the screen the ring having an extended portion positioned radially outwardly of the perforated portion.

FIG. 1

FIG. 2

FIG. 3

PLUG PROTECTION SYSTEM AND METHOD

CROSS REFERENCE TO RELATED APPLICATION

This application claims priority to U.S. Provisional Application No. 61/052,919, filed on May 13, 2008, the entire contents of which are incorporated herein by reference.

BACKGROUND OF THE INVENTION

It is common to plug fluidic openings, such as, screens, perforations and flow ports, for example, formed in tubular walls of drillstring members while the tool is being run down-hole. Plugging of such flow ports prevents borehole fluids from infiltrating the drillstring during the running process, thereby reducing the weight of the drillstring through the buoyancy forces generated by wellbore fluid upon the drillstring. Further, lower density fluids can be contained within the string to adjust buoyancy. These buoyancy forces can be particularly helpful when running a tool into a highly deviated or horizontal wellbore in reducing frictional forces between the tool and the wellbore by floating the tool into position.

However, scraping of the drillstring along at least some of the walls of a wellbore during running is unavoidable. Such scraping abrases materials used to plug flow openings often weakening such plugging to the point of failure, thereby allowing fluid to fill the drillstring, negating the buoyancy effect and benefits resulting therefrom. Consequently, systems and methods assisting the reliable running of tools would be well received in the art.

BRIEF DESCRIPTION OF THE INVENTION

Disclosed herein is a downhole plug protection system. The system includes, a tubular having perforations in a perforated portion, a screen in fluidic communication with the tubular, and a ring in sealable communication with the tubular and attached to the screen the ring having an extended portion positioned radially outwardly of the perforated portion.

Further disclosed herein is a method of protecting a plugged perforated tubular while running downhole. The method includes, perforating a portion of a tubular, sealedly attaching a ring to a non-perforated portion of the tubular, perimetrically surrounding a perforated portion with a longitudinally extended portion of the ring, plugging the perforations, and running the plugged perforated tubular downhole.

Further disclosed herein is a method of making a protected and plugged perforated tubular. The method includes, perforating a portion of a tubular, sealedly attaching a ring to a non-perforated portion of the tubular, perimetrically surrounding a perforated portion with a longitudinally extended portion of the ring, and plugging the perforations.

BRIEF DESCRIPTION OF THE DRAWINGS

The following descriptions should not be considered limiting in any way. With reference to the accompanying drawings, like elements are numbered alike:

FIG. 1 depicts a partial cross sectional view of a plug protection system disclosed herein illustrated in a plugged condition;

FIG. 2 depicts a partial cross sectional view of the plug protection system of FIG. 1 illustrated in an open and flowing condition; and

FIG. 3 depicts a magnified view of a portion of a plug protection system disclosed herein with an alternate embodiment of the perforated tubular as depicted in FIG. 1.

5 DETAILED DESCRIPTION OF THE INVENTION

A detailed description of one or more embodiments of the disclosed apparatus and method are presented herein by way of exemplification and not limitation with reference to the Figures.

10 Referring to FIG. 1, an embodiment of a plug protection system 10 disclosed herein is illustrated. The plug protection system 10 includes, a perforated tubular member 14, shown herein as a perforated base pipe, and a screen 18, sealedly attached to the perforated tubular member 14, by end rings 22 on opposing longitudinal ends of the screen 18. The perforated tubular member 14, in this embodiment, has a wall 26 with a plurality of ports 30 extending therethrough in two 15 perforated portions 32. The ports 30 are openings through which fluid, such as wellbore fluid, is flowable when the ports 30 are not plugged. The ports 30 may be any of a variety of shapes, such as, round, oval, or rectangular (to form slots), for example. The ports 30 are sized to be fluidically pluggable by any of a variety of downhole degradable materials 34, such as 20 paraffin, and/or polymers, for example, that are used for such purposes. The degradability of the materials 34 allows the ports 30 to be opened sometime after being positioned at a desired location within a wellbore 38. The degradable materials 34 may be degradable in response to exposure to elevated 25 temperatures, for example, that permit a well operator to open the ports 30, when desired, by pumping steam (or other heat source in the case of a heat degradable material) downhole to heat the perforated tubular member 14 and the degradable material 34. Alternate degradable materials 34 include materials 30 that degrade when exposed to acid or other chemical compositions. Acid, for example, can be pumped downhole to expose the materials 34 thereto when opening of the ports 30 is desirable.

35 Longitudinal extensions 42 of the end rings 22 extend 40 perimetrically to surround the perforated portions 32 of the perforated tubular member 14. As such, the longitudinal extensions 42 protect the perforated portions 32 from direct contact with walls 46 of the wellbore 38. By preventing abrasion of the degradable material 34 against the walls 46, 45 seal integrity of the degradable material 34 in the ports 30 can be maintained.

40 A length of the longitudinal extensions 42 can be designed to match a length of the perforated portions 32, so that none of the ports 30 are exposed to direct abrasive contact with the walls 46. Discontinuous non-sealing standoffs 50 can be positioned 50 between the longitudinal extensions 42 and the perforated tubular member 14 to provide structural support and centering of the longitudinal extensions 42 relative to the perforated tubular member 14.

55 Additionally, an annular space 52 defined by the longitudinal extensions 42 and the perforated portions 32 could also be plugged with plugging material 34 to increase pressure differentials required to extrude the plugging material 34. Having this additional volume of plugging material 34 could 60 also increase a time exposed to elevated temperatures or acid before the plugging material 34 sufficiently degrades to be forced through the ports 30.

65 Referring to FIG. 2, a flow path for wellbore fluid from the wellbore 38 to an inside of the perforated tubular 14 is illustrated in a non-plugged configuration of the plug protection system 10. The fluid flows through the screen 18 and then axially, along arrows 62, in an annular space 54 defined by the

screen 18 and a non-perforated portion 58 of the perforated tubular member 14. The fluid then flows longitudinally from the annular space 54 to the annular space 52. From the annular space 52 the fluid is able to flow radially inwardly, along arrows 68, through the ports 30 in the perforated portions 32 to the inside of the perforated tubular member 14. Although the fluid flow path has been described herein as flowing from outside of the plug protection system 10 to the inside of the perforated tubular member 14, it should be understood that, in other applications, the fluid could flow in directions that are the reverse of those described herein.

Referring to FIG. 3, an alternate embodiment of a perforated portion 72 of the perforated tubular member 14 is illustrated. The perforated portion 72 includes ports 76 that are designed to increase a pressure differential sufficient to force the degradable material 34 to extrude through the ports 76. The ports 76 have tapered walls 80 that create a larger cross sectional area 84 at the outer surface 88 of the perforated tubular member 14 than the smaller cross sectional area 92 at an inner surface 96 of the perforated tubular member 14. This construction creates a wedging action as the pressure differential compresses the degradable material 34 as it forces it through the ports 76. The tapering of the walls 80, in alternate embodiments, could be tapered at angles different to those disclosed herein. The walls 80 could even be tapered to narrow at locations having greater radial dimensions to increase an extrusion pressure biased in an inside to outside direction, for example.

While the invention has been described with reference to an exemplary embodiment or embodiments, it will be understood by those skilled in the art that various changes may be made and equivalents may be substituted for elements thereof without departing from the scope of the invention. In addition, many modifications may be made to adapt a particular situation or material to the teachings of the invention without departing from the essential scope thereof. Therefore, it is intended that the invention not be limited to the particular embodiment disclosed as the best mode contemplated for carrying out this invention, but that the invention will include all embodiments falling within the scope of the claims. Also, in the drawings and the description, there have been disclosed exemplary embodiments of the invention and, although specific terms may have been employed, they are unless otherwise stated used in a generic and descriptive sense only and not for purposes of limitation, the scope of the invention therefore not being so limited. Moreover, the use of the terms first, second, etc. do not denote any order or importance, but rather the terms first, second, etc. are used to distinguish one element from another. Furthermore, the use of the terms a, an, etc. do not denote a limitation of quantity, but rather denote the presence of at least one of the referenced item.

What is claimed is:

1. A downhole plug protection system, comprising:
a tubular having perforations in a perforated portion the perforations being plugged with a degradable material; a screen in fluidic communication with the tubular; a ring in sealable communication with the tubular and attached to the screen the ring having an extended portion positioned radially outwardly of the perforated portion; and

a space between the perforated portion and the extended portion being plugged with a degradable material.

2. The downhole plug protection system of claim 1, wherein the perforated portion after being plugged is openable in response to degradation of the degradable material.

3. The downhole plug protection system of claim 2, wherein the degradable material is degradable at elevated temperatures.

4. The downhole plug protection system of claim 2, wherein the degradable material is degradable when exposed to acid.

5. The downhole plug protection system of claim 1, wherein the screen is positioned radially outwardly of a non-perforated portion of the tubular.

6. The downhole plug protection system of claim 1, wherein the perforations are holes with a shape that is one of circular, oval and rectangular.

7. The downhole plug protection system of claim 1, wherein cross sectional areas of the perforations are greater at locations with greater radial dimensions than at locations with lesser radial dimensions.

8. The downhole plug protection system of claim 1, wherein the space is annular.

9. A method of protecting a plugged perforated tubular while running downhole, comprising:

perforating a portion of a tubular;
plugging the perforations with degradable material;
sealedly attaching a ring to a non-perforated portion of the tubular;

perimetricaly surrounding the perforated portion with a longitudinally extended portion of the ring;
plugging an annular space defined between the longitudinally extended portion of the ring and the perforated portion with degradable material; and
running the plugged perforated tubular downhole.

10. The method of protecting a plugged perforated tubular while running downhole of claim 9, further comprising attaching a screen to a longitudinal end of the ring.

11. The method of protecting a plugged perforated tubular while running downhole of claim 10, further comprising perimetricaly surrounding a non-perforated portion of the plugged perforated tubular with the screen.

12. A method of making a protected and plugged perforated tubular, comprising:

perforating a portion of a tubular;
plugging the perforations;
sealedly attaching a ring to a non-perforated portion of the tubular;
perimetricaly surrounding the perforated portion with a longitudinally extended portion of the ring; and
plugging an annular space defined between the perforated portion and the longitudinally extended portion of the ring.

13. The method of making a protected and plugged perforated tubular of claim 12, wherein the perforating the portion of the tubular includes tapering walls of the perforations so that an outer radial portion of each perforation has a greater cross sectional area than an inner radial portion.
